(57) **CLAIM**

The ornamental design for the cleaning tool, as shown.

DESCRIPTION

FIG. 1 is a top, front perspective view of an exemplary embodiment of a cleaning tool according to the present disclosure shown in a retracted position;

FIG. 2 is a top, rear perspective view of the cleaning tool of FIG. 1;

FIG. 3 is a first side view of the cleaning tool of FIG. 1;

FIG. 4 is a second, opposite side view of the cleaning tool of FIG. 1;

FIG. 5 is a top view of the cleaning tool of FIG. 1;

FIG. 6 is a bottom view of the cleaning tool of FIG. 1;

FIG. 7 is a rear view of the cleaning tool of FIG. 1;

FIG. 8 is a front view of the cleaning tool of FIG. 1;

FIG. 9 is a top, front perspective view of the cleaning tool of FIG. 1 shown in an extended position;

FIG. 10 is a top, rear perspective view of the cleaning tool of FIG. 9;

FIG. 11 is a first side view of the cleaning tool of FIG. 9;

FIG. 12 is a second, opposite side view of the cleaning tool of FIG. 9;

FIG. 13 is a top view of the cleaning tool of FIG. 9;

FIG. 14 is a bottom view of the cleaning tool of FIG. 9;

FIG. 15 is a rear view of the cleaning tool of FIG. 9; and,

FIG. 16 is a front view of the cleaning tool of FIG. 9.

The broken line showing is included for the purpose of illustrating and forms no part of the claimed design.

1 Claim, 10 Drawing Sheets
